US0D1087938S

(12) **United States Design Patent** (10) **Patent No.:** **US D1,087,938 S**
(45) **Date of Patent:** **** Aug. 12, 2025**

(54) **REMOTE CONTROL**

(71) Applicant: **TECH4HOME, LDA**, São João Da Madeira (PT)

(72) Inventor: **Rosa Mariana Pinto Couto**, Fiães (PT)

(73) Assignee: **TECH4HOME, LDA**, Sao Joao Da Madeira (PT)

(**) Term: **15 Years**

(21) Appl. No.: **29/906,894**

(22) Filed: **Nov. 13, 2023**

(51) **LOC (15) Cl.** **14-03**

(52) **U.S. Cl.**

USPC **D14/218**

(58) **Field of Classification Search**

USPC D14/218, 440, 126, 288, 356, 388, 401, D14/432, 433, 454, 217, 240, 242, 250, D14/252, 299, 296; D13/168, 167, 373, D13/123; D26/37; D3/300, 201; D21/333; D24/209

(57) **CLAIM**

The ornamental design for remote control as shown and described.

DESCRIPTION

FIG. 1 is a front view of a remote control in accordance with the new design;

FIG. 2 is a back view thereof;

FIG. 3 is a side view thereof;

FIG. 4 is a top view thereof;

FIG. 5 is a bottom view thereof;

FIG. 6 is a front perspective view thereof; and,

FIG. 7 is a back perspective view thereof.

1 Claim, 7 Drawing Sheets
